UNITED STATES PATENT OFFICE.

ALEXANDRE DUMONT, OF PARIS, FRANCE.

WIND-MOTOR.

SPECIFICATION forming part of Letters Patent No. 400,065, dated March 26, 1889.

Application filed April 14, 1885. Serial No. 162,183. (No model.) Patented in Spain April 4, 1882, No. 3,725; in France October 17, 1882, No. 151,626; in Belgium November 30, 1882, No. 59,725; in England December 1, 1882, No. 5,743; in Germany December 14, 1882, No. 23,934; in Italy December 31, 1882, XXIX, 426, and in Austria-Hungary October 26, 1883, No. 42,864.

To all whom it may concern:

Be it known that I, ALEXANDRE DUMONT, of the city of Paris, France, have invented new and useful Improvements in Wind-Motors, (for which I have obtained Letters Patent in France, No. 151,626, dated October 17, 1882; Belgium, No. 59,725, dated November 30, 1882; Germany, No. 23,934, dated December 14, 1882; Austria-Hungary, No. 42,864, dated October 26, 1883; England, No. 5,743, dated December 1, 1882; Spain, No. 3,725, folio 409, dated April 4, 1882, and Italy, No. 426, volume 29, dated December 31, 1882,) of which the following is a full, clear, and exact description.

This invention relates to an improved system of aerial motor or atmospheric turbine. The principal advantages of this improved motor consist, first, in the form of the vanes or blades and the improved mechanism whereby it is enabled to trim or adjust itself automatically to the direction of the wind in a slight breeze of from 1.50 to 2 meters per second velocity and of producing an impelling power when exposed to a slight wind of from two to two and one-half meters velocity only; second, in the capability of moderating its speed in a self-acting manner and without other aid, thus enabling it to work without risk in the most violent tempests; third, in the arrangements for insuring a supply of oil for lubricating the whole of the frictional surfaces and keeping the apparatus in working order, which supply needs replenishing from five to six times in the year only.

The invention consists of the new combinations of parts, hereinafter more fully specified.

The invention is illustrated by way of example in the accompanying drawings, wherein—

Figures 1 and 2 are face and side views showing the improved construction of motor wheel and framing as designed for mills of small or medium size in which the motion is transmitted by wheel and pinion gear. Fig. 1bis is a side view of the motor-wheel, the vanes or blades being removed. Figs. 3 to 5 represent one of the vanes or blades of the improved motor. Figs. 6 to 10 show portions of one of these improved motors mounted on lubricating bearings and of slightly-different

arrangement to that represented in Figs. 1 and 2, a rectilinear reciprocating motion being in this case transmitted by an eccentric on the motor-shaft; also a compensating and adjusting mechanism, which increases the power of the motor. Figs. 11 to 18bis show details of lubricating bearings eccentric and mode of pivotal suspension of the apparatus represented in Figs. 1, 2, and 6; and Fig. 19 is a vertical central section of the apparatus.

I will first describe generally the atmospheric turbine represented in Figs. 1 and 2. As will be seen in these figures, the whole apparatus is supported upon a hollow column, A. In a step upon the top of the said column A is a steel pivot, upon which is hung the frame B, which in turn supports all the other parts of the motor and is free to turn automatically by the action of the wind, the blades being self-directing. The shaft D of the motor-wheel E is supported in the bearing C and guide-bearing *u*, being counterbalanced by the weight F.

G, Figs. 1 and 2, is a bevel gear-wheel keyed to the shaft D, by which rotary motion is transmitted to a rod, H I, which passes down through the pivot and column A. Fig. 6 shows the wheel G to be an eccentric, imparting reciprocating motion to the rod H I.

I will now proceed to describe the various parts in detail.

First. The vanes or blades I now employ for the atmospheric turbine are very similar to those described in my former patent, dated March 20, 1883, No. 274,289. While based on the same principle, they are, however, distinguished by two novel features, which play an important part in their construction. I have in the first place found it more advantageous to base the arrangement of the vanes or blades upon the cotangent instead of the sinus of the angle made with the plane of rotation. I also considerably increase their breadth $o^2 o^2$ at the circumference and reduce it to zero at the center of the windmill. (See Fig. 4.) In consequence of these modifications, and in order that the importance of the novel arrangements by which the vanes thus constructed are utilized may be more readily

understood, I will proceed to fully describe one of the vanes and the manner in which it is applied. Fig. 3 shows the outline of the curve of the vane and its projection on a vertical plane perpendicular to the shaft of the mill of which it forms part. Fig. 4 shows the horizontal, and Fig. 5 the projection of the vane from the side opposite that in Fig. 3. The vanes A' , whatever may be their number, which varies according to circumstances, collectively occupy about three-fourths of the geometrical surface of the mill without, however, limiting myself thereto. Each vane A' is curved in its length from the center to the circumference (see Fig. 3) inversely to the direction of motion, so that during its rotation about point o^2 , Fig. 3, the resistance of the air thrown back by its rear face shall be equally distributed over the entire area of said face, instead of being for the several parts O^2H^2 H^2F^2 F^2D^2 D^2B^2 proportionate to the square of the velocity which each acquires during the motion, as would be the case were the vane flat instead of curved. Practically it may be constructed of the proportions represented in Fig. 3, according to a demi-parabola whose directrix and focus (a^2 b^2 c^2 d^2 f^2 e^2 g^2 h^2 i^2) vary throughout the outline, the vertex of the parabola being at the center of the mill. Each vane may be supposed to be divided transversely into an infinite number of curved lines, A^2B^2 C^2D^2 E^2F^2 G^2H^2 , Figs. 3 to 5, all of whose points are equidistant from the center of rotation, o^2 , and whose projections on a plane perpendicular to the shaft are all concentric. Each of these lines lies wholly in one plane, forming with the plane of rotation a varying angle as follows: The extreme transverse curve, A^2B^2 , of the vane toward the circumference is inclined according to circumstances and the speed to be attained, so as to form an angle of from twenty-five to thirty-five degrees with the plane of rotation. From this as a basis, the others, C^2D^2 E^2F^2 G^2H^2 , nearer the shaft are so inclined that the cotangent of the angle formed by the curve with the plane of rotation at any given point shall bear the same relation to the distance from that point to the center as the cotangent at any other given point to the distance of that from the center. Thus each vane is parallel to the shaft at the center, while midway between the center and the circumference of the mill it forms with it an angle of from forty to forty-five degrees, and at its extremity near the circumference it always forms with it an angle of from fifty-five to sixty-five degrees. A mill composed of four vanes— A' , for example—when seen transversely presents an edge or length, O^2O^2 , Fig. 5, equal to about seven-twentieths of the diameter of said mill, which dimensions are preferable to the four and five-twentieths represented in Fig. 2 of my preceding patent. This length O^2O^2 would be proportionately reduced as it approaches the center, so that all the lines $a^2b^2c^2d^2e^2f^2$, &c., drawn parallel

to the shaft on the lateral projection, Fig. 5, shall be proportionate in length to the real distance between the shaft and the points from which the lines $a^2b^2c^2d^2e^2f^2$ start. By suitably combining the above principles in the construction of the vanes a mill is obtained which will turn at a relatively much faster rate in a light wind than when driven by a strong wind, and will always work smoothly and without shocks in the most violent tempests to which it may be exposed. Experiments made with a model one meter in diameter show that a mill entirely free and exposed unweighted to a wind traveling at the rate of two meters per second will make one revolution for every two meters traveled by the wind, and for a wind of ten meters will make one revolution for every four meters traveled by the wind. It was also proved that with a wind of from thirteen to fourteen meters velocity the mill attained its greatest speed, which is rarely exceeded, however violent may be the motion of the air-currents. The maximum speed attained by a similar mill of four meters diameter under the same conditions was from fifty to fifty-five revolutions per minute. It is thus evident that vanes of large area and of a form suited for catching the slightest breeze may be exposed without danger to the most violent tempests. Secondly. The vanes composing the windmill E, as described and as shown in Figs. 1 and 2, are mounted between a pair of ring-frames or wheels, L M, provided with spokes extending from the circumference to the vane, with cross-stays a^4 intersecting each other in the interior and with tie-rods b^4 for holding the rings rigidly apart, (see Fig. 1^{1/2}), which represents the framing L M without the vanes. The vanes A' , which are made of sheet-iron or other metal, are attached to the spokes at each point of intersection at their forward ends and to the cross-stays at their rear ends, and being held between the rings and consolidated by the cross-ties which hold the rings rigid a very strong but comparatively light structure is obtained. The mill constructed as described is, moreover, for the purpose of being more easily worked separately mounted upon a hollow spindle, A⁴, capable of being readily fitted upon the shaft D, Figs. 1 and 19, the length of which may be correspondingly reduced, while to facilitate transportation and repair in the case of large mills each ring L M, with its cross-stays b^4 and spokes, is made in sections, which may be connected together at the center and circumference.

Thirdly. The bearings C, of which Figs. 11 and 12 show sectional elevations at right angles, consist, essentially, of a roller, O, of a diameter equal to about five times that of shaft D, which turns in contact therewith. The roller O is mounted on a spindle, P⁴, turning in lubricating bearings P, which rest upon U-shaped bearings Q, each half of which is hollowed at top to embrace the shaft D, and may also serve to support the same.

When the mill has been fitted in position, the shaft D is supported entirely by the roller O, for which purpose the shaft is provided at this point with a steel bush, R, preferably 5 made in two halves to facilitate placing it in position. S is a cap bolted on the bearings Q to prevent the lifting or lateral displacement of the shaft. T is an oil-reservoir at the lower part of the bearing Q, in which a wick 10 is kept constantly in contact with the roller O by a spring. The form of the reservoir T is such as to insure any excess of oil supplied to the wick being returned thereto. U⁴ U⁴ are screws fitted in each half of the 15 bearings Q, which serve to raise the shaft D when it is desired to examine the roller O or bearings P. It will be seen that the above-described mechanism provides an exceptionally smooth rolling surface and insures a perfect 20 lubrication of the working-surfaces for a lengthened period of time. The bearings represented in Figs. 13 and 14, like that above described, is composed of a roller, r, in contact with which the shaft D revolves, the 25 shaft being provided at this point with a steel bushing, s, held in position by a cap, t. The distinguishing feature in this bearing is that the roller r is of small diameter and is, together with its journals, inclosed in an oil- 30 vessel and completely immersed in oil.

Fourthly. Fig. 15, 16, and 17 show in elevation longitudinal and transverse sections relatively to shaft D of a closed eccentric yoke, D⁴, which carries the rod H I, and is 35 connected to said shaft by the guide-slots V². A sufficient quantity of oil for two or three months is supplied to the shaft D working in the slots V² by the two rollers X X, carried by the yoke D⁴ below the shaft D, and to the eccentric G itself by two other rollers, Y, carried by the yoke D⁴, all four of which rollers are mounted on springs and turn freely on their axes and dip in a cavity made at the bottom of the eccentric box or yoke D⁴. These 45 arrangements, while insuring a supply of lubricating-oil for a lengthened period, also dispense with the necessity of placing a guide for the transmission-rod H I above and immediately below the eccentric-yoke G, which 50 is a great advantage.

Fifthly. Fig. 18 is a sectional elevation showing details of the mode of suspending the framing B. At the upper end of the column A is fitted a step, Z, (separately represented 55 in Fig. 18^{vis.}), having a tube, x, for retaining the oil, the step being provided with an opening through which the transmission-rod H I freely passes, but which is rendered oil-tight by the tube x passing through the step, and 60 being soldered in said opening. In the bottom of the step Z, which is filled with oil around said tube x, is an annular steel bush, upon which a cap, W, also similarly provided with a steel bush, is hung or supported. The 65 cap is first placed in position, after which the frame B is drawn upward by means of four adjusting-screws, with which said cap is pro-

vided and which engage the frame B until it abuts against it. The frame B will be thus hung or suspended upon an annular pivot. 70 The frame B, as before mentioned, is in equilibrium, the counter-balance F, Fig. 1, being adjusted to suit. With a view, however, to guard against the effects of sudden gusts of wind or otherwise upon the frame, said frame 75 is provided with a collar, a⁶, bolted to its under side, fitting upon an enlarged part of the supporting-column A and dipping in an annular cavity, A³, containing oil provided at this point, as shown in Fig. 18. In this manner the lubrication of the parts connected with the automatic adjustment of the mill to the direction of the wind is insured for a period of two or three months, such lubrication greatly facilitating its motion. This is evident from the fact that the apparatus when exposed to a light breeze of two meters velocity per second will shift to the extent of from twenty degrees to twenty-five degrees. 85

Sixthly. The so-called compensating mechanism is represented in Figs. 6, 7, 8, 9, and 10, and consists of a toothed wheel, l, keyed on the mill-shaft D, or upon an intermediate shaft receiving motion therefrom, which drives at the rate of two turns to one of said wheel, 95 a pinion, m, hung in suitable bearings, which pinion actuates a lever-arm, n, provided with a weight, p, suitable to the power of the mill. The advantages of this arrangement will be seen by examining with regard to a certain 100 number of positions comprising one revolution of the eccentric the action of the latter and that of the weight p. Fig. 7 shows the eccentric in the middle of its upward movement, which demands of the driving-shaft D 105 a maximum effort to overcome the resistance opposed to it, at which moment the weight p falls and assists the shaft by its whole weight multiplied by the leverage. In Fig. 8 the eccentric, being at the top of its course, does not 110 absorb any power and allows full freedom of action of which the shaft is capable, and leaves the whole power of the shaft available, which power is absorbed by the weight p, which in rising offers a maximum resistance. 115 In Fig. 9 the eccentric is in the middle of its downward course, and in Fig. 10 in its lowest position presenting situations similar to those of Figs. 7 and 8. The compensating mechanism above described thus forms a new kind 120 of fly-wheel for storing the power of the motor unutilized at the end of the course of the eccentric and rendering this power available at the desired moment for carrying it past the dead-points. Its utility is particularly 125 evident in light winds, when the mill turns slowly and cannot itself perform the office of a fly-wheel.

Having now described my invention, what I claim is—

1. The rotary vane of a wind-motor constructed on the demi-parabola a² b² c² d² e² f² g² h² i² and forming the curves A²B²C²D²E²F² G²H², said curves lying in planes that form

varying angles with the plane of rotation, the cotangent of the angle formed by the plane of each curve with the plane of rotation being proportionate to the distance between each 5 curve and its center, as specified.

2. In a windmill, the combination of the wind-wheel E and its shaft D, having steel bushing R, with the supporting-roller O, bearings P P, oil-chamber T, containing a wick 10 that contacts the roller O, and screws U⁴ U⁴, whereby the shaft D may be adjusted with relation to the roller O, as specified.

3. The wind-wheel E and its shaft D, combined with the eccentric G, eccentric-yoke D⁴, 15 having slots V², through which the shaft D passes, roller X, that engages the shaft D to lubricate the same, roller Y, that engages the eccentric G, and rod H I, substantially as herein shown and described.

20 4. The wind-wheel E and its shaft D, combined with the swiveled supporting-frame B, post A, passing through and supporting the frame B, cap W secured to the frame B over the post, and the annular step Z, surrounded 25 by the cap W and carried by the post A within its upper end, substantially as herein shown and described.

5. The wind-wheel E and its shaft D, combined with the swiveled supporting-frame B, post A, passing through and supporting said 30 frame, cap W secured to the frame B, annular step Z, carried by the post A at its upper end and within the cap W, collar a⁶ on frame B at a distance below the cap W, and with an annular cavity, A³, on the post A, into 35 which said collar a⁶ dips, as specified.

6. The wind-wheel E and its shaft D, combined with the toothed wheels l m, the wheel l being driven by the shaft D, and the wheel m driven by the wheel l, lever-arm n, actuated 40 by the wheel m, weight p on the arm n, eccentric G on the shaft D, and rod H I, connected with the eccentric G, substantially as herein shown and described.

The foregoing specification of my improvements in wind-motors signed by me this 19th day of March, 1885. 45

ALEXANDRE DUMONT.
